LEWIS M. McCALLUM, OF WORCESTER, MASSACHUSETTS, ASSIGNOR TO PARKER WIRE GOODS COMPANY, OF WORCESTER, MASSACHUSETTS, A CORPORATION OF MASSACHUSETTS.

BIRD-CAGE HOOK.

1,170,919.

Specification of Letters Patent.

Patented Feb. 8, 1916.

Application filed July 9, 1915. Serial No. 38,967.

To all whom it may concern:

Be it known that I, LEWIS M. McCALLUM, a citizen of the United States of America, residing in the city of Worcester, county of Worcester, and State of Massachusetts, have invented certain new and useful Improvements in Bird-Cage Hooks, of which the following is a specification.

This invention relates to hooks such as are commonly used to support bird cages and the like from a wall.

An object of the invention is to provide a hook of the class described in which strength and rigidity are combined with low cost of manufacture.

Another object is to provide a hook which is readily attachable and detachable from its support.

In general, my device comprises a hook formed from a single piece of wire which is bent to form a horizontal rearwardly extending arm, and another rearwardly extending arm inclined thereto. Each of these arms has a vertically bent end which engages in a socket member attached to the wall. This socket member comprises a plate suitably formed with a socket portion by a single stamping operation. In engagement with each arm of the hook is a strut member which is slideable along the arms in one direction to remove the bent ends from the socket member and in the other direction to retain the ends in the socket member.

My device thus comprises only three parts, each of which can be formed by a very simple operation. The socket member may be struck up from sheet metal at a single operation. The hook and strut are formed of wire and the only operation necessary in their manufacture is simple bending. Thus the individual parts of my device lend themselves readily to low cost of production.

The entire device, when manufactured in quantities may be sold for a few cents as against the more elaborate and higher priced articles in use heretofore.

In the accompanying drawings: Figure 1 is a side elevational view of my improved hook assembled in the socket member; Fig. 2 is a sectional view taken on the line 2—2 of Fig. 1 looking in the direction of the arrows; Fig. 3 is a rear elevational view of the socket member; Fig. 4 is a sectional plan view taken on the line 4—4 of Fig. 3.

Referring to the drawings in detail: 1 repre-

resents a flat plate of sheet metal or other suitable material which is formed in the shape shown in Figs. 2 and 3. Centrally and vertically arranged on this plate 1 is a socket portion 2 and above and below the latter are screw holes 3 whereby the plate may be attached to a wall. The socket 2 as well as the holes 3 may be formed at a single operation. Thus the portion 2 may be struck up by stamping at the same time that the holes 3 are being punched and the plate itself is being formed in the contour shown. It will be seen that the operation necessary to form the plate 1 and socket 2 is a very simple one.

The hook, as heretofore mentioned, is made up from a single piece of wire. This wire is bent as follows: Starting from a short vertical end 9, the wire is bent perpendicularly to form a horizontal arm 4 which may extend to any suitable or desired distance. The wire is then bent downwardly and a semi-circular portion 5 is thereafter formed after which the wire is brought upwardly and bent backwardly upon itself at 6. The wire is then brought around in contact with the semi-circular portion 5 serving to strengthen the hook portion formed thereby. Finally the wire is brought rearwardly in inclined relation to the portion 4 as shown at 7 and is formed at its end with a short upturned vertical end 8.

The ends 8 and 9 are in vertical alinement and are adapted to engage in the socket 2 as clearly shown in Fig. 1. The wire forming the hook is so bent that the ends 8 and 9 are held in engagement with the socket portion 2 by a natural spring action in the wire. To insure the retention of these ends 8 and 9 within the socket a member 10 is used. The latter is made of wire and is bent to form eyes 11 and 12. The eyes 11 and 12 engage the wires 4 and 7 respectively and the member 10 is slideable along these wires in either direction. Thus by sliding the member 10 to the left as viewed in Fig. 1, the ends 8 and 9 are positively forced in the socket and are thereafter retained in this position due to the frictional engagement of the eyes 11 and 12, with the portions 4 and 7 of the hook. By moving the element 10 to the right it will be seen that the portions 4 and 7 are spread apart with the point 6 acting as a pivot point. This action continued will remove the ends 8 and 9 from the socket 2.

110

It is to be noted that the member 10 has in addition to its functions above outlined, the effect of a strut. The member 10 connects the portions 4 and 7 and ties the same together, thus effectually bracing the structure. The inclined portion 7 is arranged to take the thrust due to a weight on the hook 5 and transmit the latter to the wall plate 1. The entire hook is arranged to produce a strong and rigid hook with the greatest economy of material.

Thus, I have provided a simple strong and rigid hook which may be produced at a minimum cost with a maximum economy in material.

It is understood that many modifications may be made in the structure disclosed without departing from the scope of my invention which is defined in the appended claims.

20 What I claim is:

1. A hook for bird cages and the like, comprising in combination, a wall plate adapted to be secured to a wall, a struck up socket portion thereon, a horizontal arm, another arm inclined to said horizontal arm, bent portions on each of said arms adapted to engage in said socket, the outer portions of said arms being bent to form a hook, said arms, hook and bent portions being integral parts of a single wire, and a strut member connecting said arms and movable thereon to serve to retain the bent portions in the sockets of the wall-plate.

2. A hook for bird cages and the like, com-

prising in combination, a wall plate, having 3 a single integrally formed socket portion thereon, a hook member, detachably supported in said socket portion, said member comprising a horizontal outwardly extending arm, an arm inclined thereto, a hook 4 portion, and vertically disposed bent portions on each of said arms arranged to engage in said socket portion, said arms, hook and bent portions being integral portions of a single wire, and a member connecting said horizontal and inclined arms and slidable thereon, said member adapted when moved in one direction to hold said bent portions in said socket and when moved in the other direction to remove said portions therefrom.

3. A bird cage hook and support therefor, comprising in combination, a wall-plate formed with a centrally arranged struck-up portion to provide an opening therethrough, a hook proper formed from a single piece of wire, one end having a cage-engaging portion and its opposite end bent into angular portions to engage the top and bottom part of the struck-up portion, and means comprising a slidable bar to retain the angular portions in place in the struck-up portion of the wall-plate and to furnish means to brace the members of the hook, as described.

LEWIS M. McCALLUM.
